BANDING MACHINE.

No. 391,728.

Patented Oct. 23, 1888.

UNITED STATES PATENT OFFICE.

GEORGE WATTERS, OF FALL RIVER, ASSIGNOR TO GEORGE DRAPER & SONS,
OF HOPEDALE, MASSACHUSETTS.

BANDING-MACHINE.

SPECIFICATION forming part of Letters Patent No. 391,728, dated October 23, 1888.

Application filed January 12, 1888. Serial No. 260,595. (No model.)

To all whom it may concern:

Be it known that I, GEORGE WATTERS, of Fall River, county of Bristol, State of Massachusetts, have invented an Improvement in 5 Banding-Machines, of which the following description, in connection with the accompanying drawings, is a specification, like letters on the drawings representing like parts.

This invention has for its object to provide 10 means by which to mark loop-bands employed in spinning and other machines while the said bands or the material forming or to form the bands is distended, the said bands being marked at a defined distance from their loop end, and 15 preferably while the band is distended between two points, and the devices for making and marking the loop-bands are so made as to mark the bands under like conditions of tension, so that a series of said bands used in a frame and 20 drawn to the mark and tied may be brought to the same tension. If the tension of a band when tied is too little, the yarn twisted by the spindle rotated by the said band is slack twisted. So in the effort to avoid slack-twisted 25 yarn the operators tie the bands unnecessarily taut, so that it is estimated by good authority that at least ten per cent. of the power consumed in driving spindles is due solely to too-tight banding, and when the bands are too taut 30 the wear of the spindles and bearings is excessive and very injurious, necessitating frequent renewal both of the spindles and bearings and the bands.

The essential feature of my invention is a 35 means for marking the bands at a defined distance from the loop end; and my invention consists in the combination, with a hook or holder for the loop end of the band, of a marker whereby successive bands when distended may 40 be marked at a uniform distance from their loop ends in order that the marked band may be drawn up to the mark to be tied, leaving the band at the established tension.

My invention is herein shown as embodied 45 in connection with the class of machine described in United States Patent No. 121,031, dated November 14, 1871, to which reference may be had.

Figure 1 in side elevation represents a loop-banding machine embodying my invention. 50 Fig. 2 is a top or plan view of Fig. 1. Fig. 3

is an enlarged sectional detail taken longitudinally through the machine, showing some of the parts by dotted and full lines in different positions, the carriage occupying, however, a 55 different position from that shown in Figs. 1 and 2, it being in its extreme backward or normal position. Fig. 4 shows a loop-band marked in accordance with my invention. Fig. 5 is a modification, to be referred to. Fig. 60 6 shows parts of a band marked near its open end, the band being broken out to save space upon the drawings; and Fig. 7 shows a band in the process of being tied about a spindle whirl and drum. 65

Referring to the drawings, the bed-plate A, supported upon suitable legs, has at its opposite ends and near its center suitable uprights to form bearings for parts to be described. This bed-plate, its bearings, the shaft B, having the fast pulley D and loose pulley C, the revolving head W, containing the pinions b d d, the latter being on the shanks of the twisting-hooks G G, the guide-rods U U, the slide or block J, having a hook, H, and provided with 70 projections K K, the shipper-rod S, having attached to it the belt-guide E, the shipper-handle F, the arm L', fast upon the shipper-rod, the rod T, its attached stop I, to engage and prevent the rotation of the revolving head W 75 while the two halves of the band are being first twisted preparatory to being doubled together, the arm L, attached to the said rod T, the pulley P, and the weight Q are all substantially the same as in the said patent, wherein like devices are designated by like letters. 80

The weight Q is connected to the rear side of the slide J by a cord, as a, the weight normally keeping the hubs a' of the slide against the springs a', resting against the collars O, 90 secured in adjustable manner to the guide-rods U.

The shipper-rod S is free to both slide and oscillate to a limited extent. This rod has attached to it near one end a collar, b, and is extended through the spring R, the spring normally acting to move the rod in the direction of the arrow 2 near it in Fig. 1, the said spring moving the rod in that direction to shift the usual driving-belt from the fast to the loose 95 pulley whenever the toe 3 (see Fig. 1) of the shipper-handle F is disengaged from the hold- 100

ing-plate *c*, fast to the bed-plate *A*, the said toe being removed from the said holding-plate by an oscillatory movement of the said shipper-rod *S* through the action against the arm *L'* of 5 the beveled projection *K'*, attached to the slide *J*, when the slide arrives at the extreme of its movement to the right, (viewing the drawings,) that taking place while the said slide is being moved forward and the two halves of the band 10 are being doubled together. The forward ends of the guide-rods *U* are supported in the uprights *c'* and their rear ends in the uprights *c''*, portions of the said uprights below their upper ends also forming bearings for the rods *S* 15 and *T*. The slide *J* has a depending portion, *4*, to which is pivoted at *5* a loop-like catch, *e*. The bed *A* of the machine has erected upon it a hollow post or upright, *f*, which receives a rod, *g*, provided, as herein shown, above the 20 post with projections *6*, which receive upon them a marker-holder, *g'*, the said marker-holder receiving a crayon, chalk, or other suitable marking substance, as *7*, which, when brought against the band, will mark the same. 25 The lower end of this rod *g* has an arm, *g''*, which is extended outwardly through the said post *f* and has connected to it loosely a link, *g''*, which is in turn jointed to the short arm of a lever, *g'''*, connected, as herein shown, by a slot- 30 and-pin connection with the slide-bar *h*, the lever *g'''* having connected to it one end of a strong spiral spring, *g''''*, which is attached to a stud, *8*, on the bed-plate, so that the said spring normally acts to keep the rod, the holder, and 35 a suitable crayon or chalk, *7*, together with the lever *g''''*, in the dotted-line positions shown in Fig. 2, or out of operative position. The slide-bar *h* is extended through and guided by suitable guide-loops, *h'*, screwed one to the bed-plate and the other to a plate, *c'*, attached to the bed-plate. The forward end of the slide-bar is turned upward to constitute a hook, as *h''*. (Shown best in Fig. 3.) The uprights *c'* are herein shown as rising from the plate *c'*, attached to the bed-plate by suitable screws. 40 The left-hand side of this plate *c'* (see Figs. 2 and 3) has ears which receive a pin or stud, *10*, upon which is pivoted a slotted catch-lifter, *m*, the upturned end *h''* of said bar *h* normally standing in the slot of the said catch-lifter, with its end above the top of the said lifter, as shown in Fig. 3 by full lines, except when the said lifter is elevated by the sliding wedge or cam *m'*, to be described. The bed 45 of the machine has also connected to it by a screw, as *12*, a spring-like finger, *e''*, which serves as a support for the catch during part of its movement, the said finger extending forward over the catch-lifter *m*, its downturned 50 forward end substantially meeting the upturned end *h''* of the bar *h*.

The hub of the arm *L'*, attached to the shipper-rod *S*, (see Fig. 2,) is made to enter a notch in the wedge or slide *m'*, so that when the said shipper-rod is moved to the right (viewing the drawings) to shift the belt from the fast upon the loose pulley the hub of the said arm at-

tached to the rod *S* will carry with it the wedge or slide *m'*, so that its inclined end (see Fig. 3) will act upon the downturned free end of 70 the catch-lifter *m* and raise it into the dotted-line position shown in Fig. 3, in order that the said lifter may elevate the free end of the catch *e* then beyond the free end of the finger *e''* and insure that the said catch *e* during the 75 movement of the slide *J* back to the left will pass upon the rounded front end of the finger *e''*, thus preventing the said catch *e* from catching the end *h''* of the bar.

The drawings, Figs. 1 and 2, by full lines 80 show the parts of the machine in the positions they will occupy just as the carriage has started to go back immediately after the two twisted strands *s s* of the band are brought together, the marker being at that time operated to mark 85 the bands, as at *a''*. In Fig. 3 the catch *e* is in its normal position with the carriage way back, the upper end of the arm *14*, attached to the rod *T*, at such time occupying a position close to the hub *a'* of the slide *J* and against the 90 inner beveled side of the projection *K*, the said beveled projection in the backward movement of the slide *J* by the strain of the weight *Q* acting upon the said arm *14* to oscillate the shaft *T* far enough to place the stop *I* in position to engage the revolving-head *W* and prevent its rotation, as in the said patent, when the shaft *B* is again started.

In operation the material to be twisted into a band has its ends secured to the hooks *G*, projecting from the pinions *d*, and the central portion of the material is engaged with the hook *H*. In this condition, the carriage being back in the position, Fig. 3, the operator engages the handle *F*, moves the shipper-rod *S* to the left 100 far enough to place the usual driving-belt upon the fast pulley *D*, and thereafter the shaft *B* is rotated, so that the pinion *b* rotates the pinions *d*, and the revolving head *W* being held stationary the hooks *g* twist each one-half of 105 the band extended to and about the hook *H*. As the two halves of the band are twisted independently, the material forming the band is gradually shortened and the slide *J* is drawn toward the right until the front edge of the 110 projection *K* meets the arm *L* and turns the rock-shaft *T* far enough to release the stop *I* from the revolving head *W*. During this first forward movement of the slide *J* the hooked 115 catch *e* passes just beyond the end of the latch *e''* and drops down upon the lifter *m* just in front of the upturned end *h''* of the bar *h*. As soon as the revolving head *W* is released, it commences to rotate with the shaft *B*, and as it rotates it commences to unite the two halves 120 of the band together between the hooks *H* and *G*. At the commencement of this doubling 125 operation the band is somewhat slackened and the weight *Q* draws the slide *J* back for a slight distance, and in so drawing back the slide the catch *e* engages the upturned end *h''* of the bar *h*, and through it turns the lever *g''''* and link *g''*, quickly throwing the marker around into the 130 full-line positions, Figs. 1 and 2, to mark the

band, holding the marker in such position for a short space of time while the two halves of the band are being doubled together. After the two halves of the bands have been twisted 5 together near the hook H the band begins again to shorten and draw forward with it the carriage J and its attached catch e, and at such time the spring g⁵ acts to return the marker into its dotted position. During this second 10 forward movement of the slide J the catch e travels to about the position shown by dotted lines, Fig. 3, and during the second forward movement of the carriage after the two halves of the band have been properly doubled to 15 together the inclined projection K' acts against the cam m', attached to the shipper-rod S, rocking the same in its bearings and releasing the toe 3 of the shipper-rod F from the holder e, permitting the spring R to move the said ship- 20 per-rod longitudinally to the right, at which time the hub of the arm L, in engagement with the wedge or slide m', carries the said wedge or slide forward with it to the right, causing it to raise the lifter m into its dotted-line position, so that when the operator removes the 25 twisted band from the hook H and the slide J is being drawn back into its normal position by the weight Q the hooked end of the catch e will not engage the hooked end h³ of the bar 30 h, but will be elevated by the lifter m, so that the catch will ride up over and upon the front end of the finger e³ and pass back into its full-line position. (Represented in Fig. 3.)

I have herein shown my invention as applied to a known machine devised for the manufacture of loop-bands; but I do not desire to limit my invention to its application to or embodiment with a machine or apparatus of the exact form illustrated, nor do I desire to 35 limit my invention to the exact construction of marking mechanism or devices—as, for instance, a simple form of my invention might be expressed by a hook or holder, H, as shown in Fig. 5, it holding the central part of the band 40 while the same is being twisted in any usual manner, and the marking substance, 7, supported by a suitable holder, 7*, the movement of which is by a lever, 72, or by a movement 45 of the band across the marker, causing the band to be marked, as at a¹⁰, Fig. 6.

Fig. 3 shows the band in the process of being tied about a spindle and drum of usual construction, as fully explained in my application, Serial No. 260,526, filed January 12, 1888. 55 To obtain the best results and the most rapid work, the band will be held uniformly by a standard weight and the marker 7 will be operated automatically by power.

Fig. 4 shows a loop-band twisted and marked 60 at a defined distance from the looper m, the mark being shown at a². This band, when to be applied to the spindle and drawn, will be untwisted at its end opposite the loop until the mark is reached, and then one strand, or 65 half of the band, will be passed through the loop and drawn up and tied to the mark. This may be done quickly, and thus enable

all the bands to be applied at a standard and at the same tension. By the term "marker" I desire to designate the holder or device to 70 receive or hold the marking substance and a support for it.

I claim—

1. A hook or holder to hold the loop end of a band, combined with a marker by which to 75 mark the said material of the band while held at its loop end, substantially as described.

2. A hook or holder to hold the loop end of the band and a marker, combined with means to twist the material entering into the formation of the band, and with means for bringing the band and marker together to mark the band, substantially as described. 80

3. In a machine for twisting loop-bands, the hooks G, means to rotate and revolve 85 them, a holder, H, and means to support it, combined with a marker and with means, substantially as described, to actuate the marker to mark the band at a definite distance from the said hook or holder H, substantially as 90 described.

4. The hooks G, means to rotate and revolve them, the hook or holder H, the block or slide upon which it is mounted, guides for the slide, the catch pivoted upon the slide, 95 the slide-bar having an upturned end, and a marker, substantially as described, and means to connect the slide-bar with the marker, combined with the finger, lifter, and wedge or slide, and with means to actuate the said wedge 100 or slide, substantially as described.

5. The guide-rods, the slide mounted thereon, its attached catch, and a weight to draw the slide in one direction, combined with a draw-bar having an upturned end, as h³, and with 105 the marker, and means to connect the said draw-bar and marker, substantially as described.

6. The guide-rods U, the slide thereon, the hook H, the inclined projection K, connected 110 with the slide, the revolving head, the hooks G, carried by it, the rock-shaft T, having the stop I, and arm L, combined with the marker, the slide-bar, means to connect the slide-bar and marker, and the catch e, to operate the 115 slide bar, substantially as described.

7. In a machine for marking loop-bands, a hook or holder for the doubled or loop end of the band, a movable block to which the said hook or holder is attached, and a weight to act 120 upon the said hook or holder with an established weight and twisting mechanism for the bands, combined with marking mechanism, substantially as described, to mark the said bands or the material comprising the same 125 while in the machine, as shown and described.

In testimony whereof I have signed my name to this specification in the presence of two subscribing witnesses.

GEORGE WATTERS.
